Fig. 3

Fig. 4

FIG. 1 is a perspective view of a pedestal for utility meters and the like illustrating my new design with an electric meter indicated in phantom for illustrative purposes only;

FIG. 2 is a front view of the pedestal of FIG. 1;

FIG. 3 is a side view of the pedestal of FIG. 1; and

FIG. 4 is a plan view of the pedestal of FIG. 1.

The pedestal for utility meters and the like is characterized by a generally upright and rectangular configuration having a recessed planar mounting surface at the upper end thereof bounded laterally by forwardly extending flanges.

I claim:

The ornamental design for a pedestal for utility meters and the like, substantially as shown and described.
